IMPROVEMENT IN GATES.

ISAAC J. GRAY, OF SEVILLE, OHIO.

Letters Patent No. 59,743, dated November 20, 1866.

SPECIFICATION.

TO ALL WHOM IT MAY CONCERN:

Be it known that I, ISAAC J. GRAY, of Seville, Medina county, and State of Ohio, have invented a new and improved mode of securing and hanging gates, and I do hereby declare that the following is a full and exact description thereof: the nature of my invention, consists in the double pivot revolving hinge, by means of which the gate is hung, making a very useful and convenient mode of hanging gates.

The drawings hereunto annexed exhibit the structure of the gate and the mode of hanging the same, by means of the double pivot revolving hinge, which may be applied in hanging all kinds of gates. The drawing No. 1 is a perspective view of the gate, with the double pivot revolving hinge attached thereto; drawing No. 2 represents the gate while changing from a horizontal to a perpendicular position while in the process of opening; drawing No. 3 represents the perpendicular position of the gate when open. The said double pivot revolving hinge is constructed of wood and adjusted as will be seen in the drawing, or it may be made of any kind of metal or any kind of substance that will substantially produce the intended effect.

What I claim, therefore, as my invention, and desire to secure by Letters Patent, is—

The double pivot revolving hinge, and the mode of its application to the hanging of gates as described.

ISAAC J. GRAY.
